UNITED STATES PATENT OFFICE

91,219

DESIGN FOR A RADIOCABINET

Miller Stansbury, Washington, D. C.

Application November 6, 1933. Serial No. 49,661

Term of patent 14 years

To all whom it may concern:

Be it known that I, MILLER STANSBURY, a citizen of the United States, residing at Washington, in the District of Columbia, have invented a new, original, and ornamental Design for Radiocabinets, of which the following is a specification, reference being had to the accompanying drawing, forming part thereof.

The figure is a perspective view of a radiocabinet, showing my new design.

I claim:

The ornamental design for a radiocabinet, as shown.

MILLER STANSBURY.
